UNITED STATES PATENT OFFICE.

JOHN GEORGE SPEIDEL, OF READING, PENNSYLVANIA.

HOISTING APPARATUS.

SPECIFICATION forming part of Letters Patent No. 240,782, dated April 26, 1881.

Application filed March 19, 1881. (No model.)

To all whom it may concern:

Be it known that I, J. GEORGE SPEIDEL, of Reading, in the county of Berks and State of Pennsylvania, have invented a new and useful 5 Improvement in Hoisting Apparatus, of which the following is a specification.

The object of my invention is to provide for lifting variable loads, to insure safety, and to compass those objects by an apparatus of portable nature.

The invention consists in a block provided with differential gearing of novel arrangement, in safety-stop devices and automatic brake mechanism, acting by weight of load, as more 15 particularly set forth hereinafter with reference to the accompanying drawings.

In the drawings, Figure 1 is a side elevation of the apparatus. Fig. 2 is a front view. Fig. 3 is a central vertical section. Fig. 4 is a vertical section on line $x-x$ of Fig. 3, showing the brake mechanism. Figs. 5, 6, and 7 are detail views of the chain-wheel.

Similar letters of reference indicate corresponding parts.

25 A is the main shaft of the mechanism, having at its ends chain-wheels a a' , on which are endless hand-chains b b . The wheel a is loose on the shaft, and has its hub formed with a pinion, c , and wheel a' , which is fast on the 30 shaft, is formed with a rim-flange and internal gear.

d is a secondary shaft carrying fast pinions e e' , that mesh with pinions c and wheel a' respectively. The shafts A d are sustained in 35 cheek-plates f f , which at the upper end are connected by a yoke or bar, g , that is fitted with a hook, h , for suspension of the apparatus. At the lower end the cheek-plates f are connected by a bar, p , on which is hung an eye-piece or ring, i .

On the shaft A, between the plates f , a chain-wheel, k , is keyed, and loose on the shaft are two wheels or disks, l l , that have their hubs extended through elongated bearings in plates f .

45 On the shaft d is loosely hung a bent guide-piece, t , that laps over the chain-wheel and prevents the chain from rising.

The hoisting-chain m passes around wheel k , and its end having the hook k' may be attached to the load, or when double power is required the chain carries the block n , and has its end connected to the ring i .

The wheels l are the brake-wheels, and are fitted with the devices next described. The wheels l have their faces next to wheel k formed with ratchet-teeth, and the wheel k , as shown in Figs. 5, 6, and 7, is provided with four spring-pawls, o , two on each side, consisting of straight pins set in mortises, with spiral springs behind them, so that they are projected and engage the 55 ratchets. The rims of the wheels l are formed with V-grooves.

As shown most clearly in Fig. 4, there are two curved toggle-bars, q q , hung on the lower cross-bar, p , beneath each wheel l , and extending around them at opposite sides. The upper ends of each pair of bars are connected by a right-and-left hand screw-rod, s , to allow of their adjustment, and the bars carry brake-blocks entering the grooves of the disk l . The 60 brake-blocks are in two portions—viz., the outer portions, r , that are attached to bars q by bolts passing through slots, as shown in Fig. 2, and the loose V-shaped portions r' , placed between the portions r and brake-wheels l . The adjustments of these parts may be made so that the 65 brake-blocks shall give exactly the pressure required to hold the load suspended from the shaft A.

In operation the load is raised or lowered 70 by operation of either hand-chain, according to the power required. The chain on wheel a' gives the greater speed, and with heavy loads 75 may be first used to tighten the hoisting-chain and the other hand-chain then used. As the 80 chain-wheel k turns in raising the load its pawls pass over the ratchets of wheels l . The load on shaft A is sustained by brake-wheels l , resting on blocks r' , which, in turn, are supported by bar p , so that the brake is continuously applied and the chain-wheels arrested by the 85 ratchet devices the moment the hand-chains are left free. In lowering the load the hand-chains are to be run backward and the chain-wheel k will then give revolution to the wheels 90 l . The load will thus be at all times under the control of the operator.

It will be seen that with this apparatus four 95 rates of speed are attainable. The apparatus is also safe and portable. It can also be made 100 of comparatively small size and used for heavy loads. The brake-wheels have sufficient holding power, though made of small size, for the reason that the whole load resting on the axle

is taken by the brake-blocks at opposite sides of the wheels. The resistance can be varied by shifting the blocks to change the angle of resistance.

Having thus fully described my invention, I claim as new and desire to secure by Letters Patent—

1. In hoisting apparatus, the combination of chain-wheel *k*, hoisting-chain *m*, chain-wheels *a a'*, hand-chains *b b*, main shaft *A*, counter-shaft *d*, intermediate gearing between the hand-chain wheels, and the sustaining-plates *f*, substantially as shown and described, combined for operation as set forth.

2. In hoisting apparatus, the loose brake-wheels *l*, formed with ratchet-teeth, chain-wheel *k*, fitted with spring-pawls *o*, toggle-bars *q*, brake-blocks *r*, suspension-plates *f*, formed with elongated bearings, connecting-bar *p*, and the operating-shaft *A*, carrying the chain and brake wheels, combined for operation substantially as shown and described. 15 20

JOHN GEORGE SPEIDEL.
